ELECTRIC IRON

James W. Steele, North Kansas City, Mo.

Application December 5, 1938, Serial No. 244,058

3 Claims. (Cl. 219—25)

The present invention relates to improvements in electrically heated irons, such as the type of iron used for laundry operations, and the primary object in view is to provide a more efficient 5 relation of the heating element in the iron, in order to distribute the effect of the heating element to all portions of the base or sole plate of the iron which it is possible to utilize for the ironing function of the device.

10 In this connection, it is also sought to devise a combination of base or sole plate of improved design in connection with the heating element therein, for the purpose of improving the outline or bottom margin of the iron so as to enable it 15 to be operated more easily and smoothly in side-wise directions as well as in forward or rearward directions.

A further object of the invention is to provide 20 an iron construction having an electric heating element, the cord attaching means for which are substantially built into the heating element, thereby eliminating many other disadvantages in the common type of iron which are subject to arcing and also have a tendency to work loose, with 25 the trouble always resulting from such defects.

With the foregoing general objects in view, the invention will now be described by reference to the accompanying drawing illustrating a preferred type of construction which I have devised 30 for embodying the present improvements, after which those features and combinations deemed to be patentable will be particularly set forth and claimed.

In the drawing—

35 Figure 1 is a side elevation illustrating an electrically heated iron having embodied therein the present features of improvement;

Figure 2 is a plan view of the sole plate portion of the iron detached from the remainder of the iron, and on a slightly larger scale;

40 Figures 3 and 4 are longitudinal and transverse sections taken on the lines 3—3 and 4—4, respectively, of Figure 2;

45 Figure 5 is a perspective view of the type of electric heating element used in the construction.

Referring now to the drawing in detail, this 50 illustrates my improved iron construction as comprising a base or sole plate member 10, upon which is mounted the upper iron portion 12, which is adapted to be secured to the base portion by means of suitable screws 14 and 14' threaded into tapped sockets 15 in the sole plate 10. The screw 14 also serves, along with another screw 16, for the attachment of a handle 18 applied to the

upper end of said screws 14 and 16 and secured by means of nuts 20, as illustrated in Figure 1.

The top face of the base or sole plate 10 is cut out to provide a channel 22 of an appropriate design, as illustrated in Figure 2, for accommodating the heating element as well as the cement and packing material 24 which is packed around the part of said element which is embedded in the iron. For effecting the heating function, I have found a heating element of the type commercially known as the "Calrod" element illustrated fully in Figure 5, this element, as is generally known, being comprised of a central current conducting core 25 and a casing 26 of protective as well as heat conducting and radiating material—see Figures 15 3 and 4. The core portion 25 of the element is provided with screw terminals 27, which in the present construction are utilized as convenient means of direct attachment of the current conducting means 30.

As illustrated in Figure 2, the shape or contour 20 of the channel 22 in the upper face of the sole plate 10 is designed to accommodate the element 26 in the coiled form shown in Figure 5, which is that arrangement of the heating element best 25 adapted to locate it in its most effective functional relation to the working face of the sole plate, i. e., at all points both with reference to the bottom surface of the iron but also the outer margins of the sole plate, including the areas 30 adjacent to the extreme ends or points 10' of the sole plate. By reference to Figures 2 and 5 it will be noted that the heating element as well as the channel 22 for embedding said element are

35 both in approximately oval form for extending in approximate conformity to the outer margin of the sole plate 10, and the end portions of the heating element are extended in re-entrant relation to its main coil portion, so as to be in heating relation to the central part of the sole plate, as indicated at 26', and moreover the extreme ends or 40 terminals 27 are arranged in upstanding relation so as to project up through suitable openings provided in the top portion 12 and leave the terminals 45 in projecting relation for the attachment of the heating cord 30 to the terminals 27 by means of suitable nuts 32, as shown in Figure 1. The attached portion of the cord 30 may be 50 shielded in the usual manner by means of a housing 34 attached at 35 to the top member 12 of the iron, the cord having the usual reinforcing coil device 36 as shown in Figure 1.

Referring to the advantages of the improved construction above described, one of the most important features is in the provision of a double

pointed iron with a heating element so arranged as to heat the sole plate or working portion of the plate entirely around its marginal surface, and including the heel portion of the iron which is ordinarily left without any provision for heating whatever. In the improved device a single heating element, such as disclosed in Figure 5, is so utilized as to heat not only the central portion of the sole plate but also the entire remaining operative portion of the working face of the iron, out practically to the extreme marginal edge thereof.

Another advantageous feature is in the particular shape or contour of the sole plate, having its lateral curves following such a contour as to permit easy and even movement of the iron by the operator in either sidewise direction, in contrast to the usual shape which is not adapted for convenient movement in such directions, on account of the square or blunt shape of the heel portion of the iron. With the improved shape as illustrated, the operator can move the iron either rearwardly or in a combined rearward or sidewise movement, but with the same facility as in any other operative direction, which is an important item of efficiency in many of the necessary laundry finishing operations.

The same improved shape of the sole plate or base member of the iron is of course just as readily applicable to other than the electrically heated type of iron, as for example with steam heated irons, with suitable provision for holes or openings in the sole plate, or without such provision as to holes, where a booster is provided for low pressure steam in order to give dry steam in the ironing operation.

The use of an electrical heating element of the type herein described has the further advantages of eliminating the use of the usual type of cord connections, using slip contacting devices which are likely to come loose, and often result in sparking or arcing, or inefficient circuit connections producing inefficient heating of the iron. The simple form of heating element as well as the provision for making connection with the heating current also enables the iron to be used, if desired, as a liquid heating means, such as to heat water in a vessel, since the iron may be dipped in the liquid below the level of the liquid to any extent so long as said level does not ex-

tend above the terminals 27 of the heating element, and without any danger of short circuiting whatever.

It will therefore be seen that I have provided a practical and efficient form of construction, as well as iron design, adapted to carry into effect all the objects of my invention, and while I have illustrated and described what I now regard as a most practical embodiment of the improved construction, I desire to reserve the right to make whatever changes or modifications may fairly fall within the spirit and scope of my invention as defined by the following claims.

Having thus described my invention, what I claim to be new and desire to secure by Letters Patent is:

1. A hand iron having a base or sole plate portion of approximately oval form provided with pointed or nose portions at its opposite ends, and an electric heating element imbedded in said base portion and comprising a coil extending parallel and in close heating relation to the edge of said base portion entirely around the iron, the terminals of said heating element extending upwardly and completely to the exterior of the iron for making direct connection with the source of the heating current.

2. A hand iron having an electric coil in its base portion, said coil being arranged in a major coil outline extending adjacent to the outer margin of the base portion and substantially the same distance from said margin entirely around said base portion, the end portions of said coil extending within the outline of the major portion in heating relation to the central working face of the base portion and providing terminals for connection with the source of the heating current.

3. A hand iron having a base or sole plate portion of approximately oval form provided with pointed or nose portions at its opposite ends, and an electric heating coil having its main coil portion extending in close heating relation to the edge of said base portion entirely around the iron and its terminal portions arranged in close heating relation to the central working face of said base portion and providing terminals for direct connection with the source of the heating current.

JAMES W. STEELE.
